UNITED STATES PATENT OFFICE

WILLIAM E. BIHL AND AXEL RAMCLAW, OF CHICAGO, ILLINOIS, ASSIGNEES, BY MESNE ASSIGNMENTS, TO ZEROZONE, INCORPORATED, A CORPORATION OF DELAWARE

FLOODED COOLING UNIT

Application filed January 22, 1930. Serial No. 422,514.

This invention relates to flooded cooling units for mechanical refrigerating plants, and has for its principal object the production of a new and improved unit of this kind.

5 In mechanical refrigerating systems, such as are now being commonly used in apartment houses, homes, restaurants, and the like, an evaporator or so-called cooling unit is installed in the refrigerator that is to be cooled by the system.

10 Within this cooling unit is a quantity of refrigerant which is withdrawn from the evaporator in the form of a vapor, and that vapor is compressed and cooled to turn it back into liquid by a compressor unit which may be individual to the evaporator or common to a group of evaporators. That liquid is returned to the evaporator, and this cycle is repeated continuously while the plant is in 20 operation.

25 In the operation of plants of this kind, a certain amount of oil is emulsified with the liquid refrigerant in the compressor and returned to the evaporator with the liquid, where it filters out of the liquid and collects 30 on the surface of that liquid in the evaporator. If allowed to remain on this surface, the oil forms a blanket which greatly retards the evaporation of the refrigerant and consequently impairs the operation of the system.

35 This collection of oil on the surface of the refrigerant in the evaporators is more pronounced in a so-called centralized unit system, that is one in which a single compressor is employed to circulate the vapor and liquid from a plurality of vaporizers or cooling units. Installations of this kind are commonly made in apartment houses, residential 40 hotels, and the like.

45 This accumulation of oil, while it is unavoidable, is at the same time advantageous, since it affords a method of lubricating the interior walls of the compressor.

50 This is accomplished by drawing the oil from the surface of the liquid in the evaporator through the suction pipe into the compressor, that withdrawal being accomplished by a skimmer connected to the pipe and disposed in juxtaposition to the surface of the liquid in the evaporator unit.

In order that the system may operate correctly, it is imperative that the suction pipe withdraw only vaporized refrigerant from the evaporator, together with the liquid oil from the surface of the liquid in that unit. 55 If liquid refrigerant is permitted to be drawn into the suction pipe, that liquid is vaporized in that pipe and this vaporization reduces the temperature of the pipe to below the dew point, causing the formation of dew or frost 60 on the pipe leading to the compressor unit. This dew or frost will melt when the temperature of the pipe again rises, and the water thus collected will drop from the pipe onto the walls of the building through which the 65 pipe runs, and damage them.

To prevent contingencies of this kind, various arrangements have been devised heretofore, and of which we are aware, to secure 70 a skimming of the oil from the liquid refrigerant in the evaporator without danger of picking up some of the liquid refrigerant as well as the oil.

75 One of the objects of our present invention is to provide a new and improved skimming arrangement wherein the oil can be skimmed from the surface of the refrigerant in the evaporator without danger of picking up any of the liquid refrigerant.

80 Evaporators have heretofore been usually constructed by placing a cylindrical tank in a horizontal position and attaching a plurality of U-shaped circulating coils to the tank. In an evaporator of the size used in an ordinary apartment house refrigerator, 85 4 or 5 of these U-shaped coils have been attached to each side of the drum, and since each of these 8 or 10 coils employed has two ends, this construction has made necessary the use of from 16 to 20 soldered joints in 90 the evaporator unit. When properly made, these soldered joints prevent the escape of refrigerant or vapor from the unit, but at the same time their presence is hazardous since, if the unit is jarred or jammed, the soldered joint is liable to break and a leak will result.

95 Furthermore, in a construction of this kind, the circulating coils are in effect in parallel with each other, so that the circulation through them is relatively slow. As is 100

well understood by those skilled in the art, the amount of evaporation of the refrigerant is a function of the temperature of the coils, and therefore for a given temperature on the 5 evaporator unit a given amount of vaporization takes place. Obviously if there are ten coils in multiple, each coil will have a circulation through it equal only to one tenth of the circulation of the entire system, since 10 that circulation is produced solely by the vaporization of the refrigerant.

This relatively slow movement of the liquid refrigerant and vaporized refrigerant through the circulating coils frequently results in at least a part of those coils becoming oil-bound due to the collection of oil on the inside surfaces of the tubes. When a tube 15 becomes oil-bound its refrigerating ability is lessened and it soon becomes practically 20 useless as a medium for cooling the refrigerator.

As a further object of our present invention, we have provided a new method of constructing circulating coils which reduces the 25 number of soldered joints necessary in the construction of an evaporator unit and also creates a more rapid flow of liquid and vapor through the circulating coils. This is accomplished by forming the coils in series rather 30 than in parallel, so that with a given amount of evaporation or vaporization of the refrigerant all of the vapor produced thereby moves through the coils in series instead of 35 in parallel as has been the practice heretofore. In one embodiment of our invention, we provide two sets of series coils leading 40 out of the drum so that there are but four soldered connections on the drum instead of the sixteen or twenty that have been used heretofore.

The boiling or vaporization of the refrigerant in the coils is thereby increased from a moderate boiling to a violent boiling, with the result that the movement of vapor 45 and liquid through the coils is rapid. This rapid movement scavages the oil from the walls of the coils and keeps them clean so that they may efficiently operate to absorb heat from the refrigerator and thereby cool it.

50 The serially related coils employed in the preferred embodiment of our invention form a rectangular area beneath the drum of the evaporator into which a freezing chamber or box is placed, that box being supported on certain ones of the loops of the serially related coils and by others of those loops. To increase the surface of the coils in thermal contact with the freezing box, we have flattened the coils of the units so that they present 55 a broad flat surface in thermal contact with the box. This insures a rapid transfer of heat from the box into the circulating coils and a consequent violent boiling of the refrigerant and therefore rapid withdrawal 60 of heat from the box.

Now to acquaint those skilled in the art with the teachings of our invention, reference is here made to the accompanying drawings in which a preferred embodiment of it is shown by way of example, and in which:

Figure 1 is a side elevational view, partly in section, of an evaporator unit showing our improved skimmer and circulating coil arrangement; 75

Figure 2 is an end view of a completely assembled evaporator unit;

Figure 3 is a front view of a completely assembled unit with the cover plate partly broken away to show the interior construction 80 of the unit;

Figure 4 is a perspective view of the float showing the details of the baffle plate of our skimmer arrangement; and

Figure 5 is a cross-sectional view taken 85 along the line 5—5 of Figure 1.

Referring to the drawings in more detail, the evaporator unit comprises the horizontal drum 1 which is conveniently made cylindrical and disposed with its axis in a horizontal position. The open end of the drum 1 is rolled into the groove 2 in an end forging collar 3, this joint preferably being also closed by silver solder or brazing to insure its tightness. The end surface 4 of the collar 3 is machined flat and affords a seating surface for the end plate 5 which is held thereon by bolts 6 and 7. The end plate 5 may be a forging or a casting in accordance with the usual practices of the art. Preferably the cylindrical drum 1, the ring 3 and the plate 5 are all constructed of brass, although other materials may be substituted therefor within the teachings of our invention. 95

On the outside end of the cover plate 5 we 105 have located the suction line valve 8 and the pressure line valve 9, in accordance with the usual practice in devices of this kind.

These valves may be any valve capable of sealing off the interior of the drum from the outside atmosphere when it is required to do so, and the particular structure of the valves per se is not of the essence of our invention. 110

Within the drum 1 we have located a float 115 10 which is hollow and preferably constructed of two seamless brass cylinders fitted end to end and soldered or otherwise fastened together to make a vapor-tight joint.

A lever 11 is welded to one end of the float 120 10 and pivoted to the end plate 5 by a pivot 12 suitably supported on that plate. A needle valve 13, attached to the projection 14 of the lever 11, is seated in a valve seat 16 that is threaded into the end plate and is in communication with the port in that plate leading to the pressure line of the system through the valve 9. Through this arrangement, the float actuates the needle valve 15 to seat or 125 unseat it upon the member 16 to thereby reg- 130

ulate the amount of liquid refrigerant admitted to the drum 1 and circulating system connected thereto.

A suction pipe 17 is threaded into the end plate 5 in communication with the suction line of the system through the valve 8, that pipe containing an oil skimming projection 18 which is bent downward and terminates in the oil film disposed upon the top of the 10 refrigerant in the drum, as will presently appear.

The suction pipe 17 is bent upward and its open end disposed adjacent the upper surface of the drum 1 in accordance with the 15 usual practice in devices of this kind.

The compressor unit of the system, not shown, emulsifies a certain amount of oil with the liquid refrigerant and that oil is returned to the evaporator with that liquid. 20 Within the evaporator this emulsified oil separates from the refrigerant, and, being lighter than the refrigerant, collects as a film 19 on the upper surface of the refrigerant.

In order that the skimmer pipe 18 may 25 withdraw this film of oil from the drum 1 without also withdrawing liquid refrigerant, it is imperative that the surface of the liquid at the point at which the pipe 18 engages it be quiet and free from agitation caused by 30 the boiling of the refrigerant. Various arrangements of baffles have been provided heretofore to secure this quiet area within the drum; however, insofar as we are aware, these devices have not completely secured the 35 desired results.

To aid in securing a quiet area from which the oil can be skimmed, we have attached a baffle plate 20 to the end of the float 10, that baffle being Z-shaped. One flange of the 40 bracket is attached to the end of the drum and the other flange disposed on the free end of the bracket substantially at right angle thereto. This attachment to the drum may be made by welding, soldering, or brazing, or 45 in any other preferred manner which rigidly attaches the baffle to the float without impairing the vapor-tightness of the float.

The baffle 20 is positioned on the drum in such a manner that its horizontal portion lies 50 beneath the surface of the oil and above the surface of the refrigerant, that is, it is embedded in the oil. This film of oil frequently is a quarter of an inch thick in a commercial installation, so that little difficulty is experienced in so locating the baffle 20 that its horizontal portion will be completely submerged in the oil.

As will be apparent, the position of the float 10 shields one end of the region defined 60 by the baffle plate 20 and therefore produces a quiet area on the surface of the oil. The flange projecting from the horizontal portion of the baffle at its free end protects the other end of this area. We have found that 65 the refrigerant in the drum 1 is comparative-

ly quiet in the region of the suction pipe 18, since the majority of the boiling takes place in the opposite end of the drum. Some boiling occurs adjacent the end plate 5 due to the ingress of liquid refrigerant through the 70 needle valve 15, but this is very moderate and the baffle plate 20 is sufficient to prevent this boiling from disturbing the oil film around the skimmer pipe 18.

In the preferred embodiment of our invention shown in the drawings, the circulating pipes are led out of the back end 30 of the drum 1, and downward therefrom through a plurality of serially related coils or loops, and return to the drum at a point in its side adjacent the end wall 30.

This arrangement concentrates the boiling of the refrigerant in the end of the drum farthest away from the oil skimmer, and we have found that the combined action of the 85 float and baffle maintain an area around the skimmer pipe 18 sufficiently quiet to permit it to skim the oil off the refrigerant without drawing up any liquid refrigerant.

In the construction of the circulating coils, 90 we bend a piece of seamless tubing, preferably copper, so that it may be attached to the rear end 30 of the drum 1 and projected straight downward to a point substantially below the lower surface of that drum. This 95 piece of tubing is then bent at right angles to the vertical portion 31 to form a loop 32 disposed in a horizontal plane beneath the drum. At the far end of the loop 32, which end incidentally is adjacent the vertical portion 31 of the pipe, we bend the pipe at an angle of 45°, as shown at 33, to bring it into a plane located outside of the periphery of the drum 1.

We next form the pipe back and forth in 10 this plane to form a plurality of loops 34, 35, 36, 37, 38 in which the pipe is disposed horizontally, as at 39, and also a portion of it is disposed at an angle to the horizontal portion, as at 40. The free end 41 of the 11 pipe is laid along the side of the drum 1 and attached thereto at the point 42 adjacent the end wall 30 of that drum.

A similar series of coils or loops are formed 11 on the opposite side of the drum by the pipe 43 which has one of its ends attached to the end plate 30 and the other end to the side wall of the drum adjacent that end plate. This pipe 43 likewise has a horizontal portion 44 and vertical portion 45 which, together with the corresponding portions of the pipe 31, form a generally rectangular box-like structure beneath the drum.

The two ends of the pipe 31 and 43 are soldered to the drum 1, preferably by silver 12 solder, although other forms of attachment may be employed so long as they insure a vapor-tight joint that is also mechanically strong. It will be noted that this construction attaches a system of circulating pipes 130

to the drum with but four soldered joints in the system, whereas a larger number has been invariably used in this device heretofore.

Within the rectangular portion formed by 5 the coiled pipe 31 and 43, we place a freezing box 50 which is a substantially rectangular copper box containing shelves 51 and 52 upon which the cube trays 53 are placed. While we prefer to construct this box of sheet 10 copper because of the better thermal conductivity of copper, obviously other metals may be employed for this purpose.

The box 50 is in thermal contact with the 15 horizontal coils 32 and 44 of the circulating system and also with the vertically disposed coils 34 to 40, inclusive, of the pipe 31 and the corresponding coils of the pipe 43. In order to increase the area of the circulating pipes in thermal contact with the box 50, we 20 have flattened the pipes so that a greater area of pipe wall is in thermal contact with the box. This flattening operation is preferably performed after the pipe has been bent into the desired shape and serves not only 25 to flatten the pipes but also to accurately align them in planar relation to each other. All of the coils of the two circulating pipes are thus flattened so that the horizontal coils 32 and 44 as well as the vertical coils have 30 large areas in thermal contact with the bottom of the freezing box 50.

In order to conceal the valves 8 and 9 disposed on the front side of the drum, we have 35 provided a cover plate 60 which is supported on the drum by screws and spaced away therefrom by spacing cylinders 61 disposed around those screws. A cover 62 disposed over the front of the freezing box 50 is attached to the cover plate 60 by hinge 63, 40 so that the freezing box may be covered if desired. The addition of this cover plate and door to the front side of the box is merely for appearance sake and in keeping with the modern practice of manufacture, 45 and can be omitted if desired without in any way impairing the efficiency of the evaporator unit.

In the operation of the unit, suction is 50 built up into suction pipe by the compressor, which may be either an individual compressor or a compressor employed to operate a plurality of evaporators, that suction withdrawing the vapors that have collected above the oil film in the drum 1 through the suction pipe 17. The suction also picks up the 55 oil disposed above the baffle 20 through the oil skimmer pipe 18 and returns the vapor and oil to the compressor unit. The refrigerant is returned from the compressor unit 60 as liquid through the pressure pipe and valve 9 where a certain amount of it is permitted to enter the drum under the control of needle valve 15. Within the evaporator unit itself, 65 the liquid refrigerant flows down into the circulating pipes, where it is made to boil by

the heat in those pipes. The boiling causes vapor to form, that vapor collecting in the form of bubbles which filter their way through the liquid in the pipes into the drum 1 and thence up through the liquid and oil film into the vapor chamber at the top of the drum, from which the vapor is withdrawn by the suction line of the system. Each of the coils of the circulating pipe is in thermo-contact with the freezing box and with the air in the refrigerator, so that it serves as a heat absorber and transfers the heat absorbed to the refrigerator to boil it. The vapor produced in each coil of the circulating pipe is 70 added to that produced in the other coils, so that the boiling produced in the coils is violent, and the circulation of the liquid refrigerant through these coils is therefore 75 rapid.

This rapid circulation of the refrigerant 80 prevents the accumulation of a film of oil on the inside surface of the circulating pipes and therefore maintains the circulating system in condition to efficiently transfer heat 85 from the refrigerator to the liquid refrigerant in the pipes.

Inasmuch as the sections 40 of the circulating pipes slope downwardly and the gas 90 in those sections must therefore flow downward, it might appear that a trap would be formed and the circulating system become 95 gas-bound. However, we have found that the 100 boiling is so rapid in the pipes that the gas flows freely through them even though it flows downward through a part of its travel, and in a commercial installation of the evaporator shown in the drawings, successful operation has been carried on over a long period of time without the box becoming either gas-bound or oil-bound.

Since the outlet and inlet portions leading 105 from the drum into the circulating pipes are both located adjacent the end 30 of the drum 1, the greater part of the boiling of the liquid refrigerant in the drum takes place 110 at that end which is remotely removed from the skimmer pipe 18. Skimming oil off of the refrigerant without drawing up liquid refrigerant is facilitated by the combined 115 action of the float, the baffle, and the concentration of the boiling in the back end of the drum to produce a quiet area around the skimmer pipe through which the oil can be skimmed.

While we have chosen to show our invention 120 by illustrating a preferred embodiment, we have done so by way of example only, as there are many modifications and adaptations which can be made by one skilled in the art within the teachings of the invention. We are therefore to be limited only by the appended claims.

What we claim is:—

1. In a refrigerating unit, an evaporator 125 comprising a closed horizontally disposed

- drum, a circulating pipe leading out of one end of the drum downward through a horizontal coil disposed beneath the drum, thence upward to said drum through a plurality of serially related substantially horizontal pipes arranged one above the other in a vertical plane, a second circulating pipe extending through a second series of serially related substantially horizontal coils, a metallic freezing box resting on the horizontal coils and between the pipes of the two series, and a means within said box for holding ice cube trays. 2. In a refrigerating unit, an evaporator comprising a closed horizontally disposed drum, a circulating pipe leading out of one end of the drum downward through a horizontal coil disposed beneath the drum, thence upward to said drum through a plurality of serially related substantially horizontal pipes arranged one above another in a vertical plane, a second circulating pipe extending through a second series of serially related horizontal coils and pipes, a metallic freezing box resting on the horizontal coils and between the substantially horizontal pipes of the two series, and a cover plate fastened to the other end of said drum and supporting a door for said box. 3. In a refrigerating unit, an evaporator comprising a closed horizontally disposed drum, a circulating pipe having its two ends attached to said drum near one of its ends, said pipe being formed into a plurality of serially related coils extending from one end of the drum to the other, one of said coils being disposed in a horizontal plane below said drum, and the other ones of said coils being disposed one above the other in a vertical plane alongside said drum, a second circulating pipe similarly attached to said drum and similarly formed into coils one of which also lies in said horizontal plane, a freezing box resting on said planar coils and between said other coils, and means in said box for holding ice trays. 4. In a refrigerating unit, an evaporator comprising a closed horizontally disposed drum, a circulating pipe having its two ends attached to said drum near one of its ends, said pipe being formed into a plurality of serially related coils extending from one end of the drum to the other, one of said coils being disposed in a horizontal plane below said drum, and the other ones of said coils being disposed one above the other in a vertical plane alongside said drum, a second circulating pipe similarly attached to said drum and similarly formed into coils one of which also lies in said horizontal plane, and a rectangular freezing box resting on said planar coils between said other coils. 5. In a refrigerating unit, an evaporator unit consisting of a horizontally disposed closed drum, a circulating pipe extending downward from an opening in one end of the drum through a horizontal loop disposed beneath the drum thence through a plurality of loops disposed in a vertical plane which is parallel to the axis of said drum and located outside its periphery, thence back into the drum through an opening disposed in its side adjacent said end, a second circulating pipe extending from a second opening in the end of the drum serially through a plurality of coils disposed in a similar manner to the first but on the opposite side of the drum through an opening in its side opposite said first side opening, and a liquid filling said pipes and said drum to a point above said openings. 6. In a refrigerating unit, an evaporator comprising a horizontally disposed closed drum having refrigerant inlet and outlet ports located in one end thereof, a plurality of substantially horizontal serially related circulating coils, a port disposed in the other end of said drum and leading into the first one of said coils, and a second port disposed in one side of said drum adjacent said other end and leading out of the last one of said coils into said drum. 7. In a refrigerating unit, an evaporator comprising a horizontally disposed closed drum having refrigerant inlet and outlet ports located in one end thereof, a plurality of substantially horizontal serially related circulating coils, disposed in a vertical plane beneath said drum, a port disposed in the other end of said drum and leading into the first one of said coils, and a second port disposed in one side of said drum adjacent said other end and leading out of the last one of said coils into said drum. 8. In a refrigerating unit, an evaporator comprising a horizontally disposed closed drum, a circulating pipe leading from one end of said drum vertically downward to a point beneath the drum, horizontally in a horizontal plane through that point and equidistant from the bottom of the drum to a point below the opposite end of the drum, back in that plane to a point adjacent said first point, upward therefrom to a plane disposed at right angles to the first plane and outward of said drum, back and forth in that plane from one end of the drum to the other, and back into said drum at a point in its side adjacent said end, and a liquid in said drum covering the ends of said pipe. 9. In a refrigerating unit, a closed drum having refrigerant inlet and outlet ports located in one end thereof, a pair of circulating pipes each leading out of a side wall of said drum adjacent the opposite end thereof and extending through a plurality of serially related coils, the last coil of each of said pipes being disposed in a horizontal plane and opening into the opposite end of said drum, a freezing box resting on said horizontal coils.

and means for supporting ice cube trays within said box.

10. In a refrigerating unit, an evaporator comprising a horizontal sealed drum, a pair of circulating pipes leading out of an end of the drum and back into it through its sides at points adjacent said end, an inlet port disposed in the opposite end of said drum, a float pivoted to said drum adjacent said inlet port, an outlet port also disposed in said opposite end, a liquid filling said pipes and drum to a height regulated by said float, and means including a baffle mounted on said float and disposed a fixed distance below the surface of said liquid, and a skimming pipe extending from said inlet port to a point adjacent said baffle for skimming said liquid.

11. In a refrigerating unit, the combination with a closed tank containing liquid which has a film of oil over its upper surface, a float for regulating the height of that liquid and oil, and a suction pipe for maintaining the remainder of the tank at a low pressure, of a baffle plate attached to the end of the float and having a substantially horizontal portion disposed above said liquid surface in said oil film, and a skimmer pipe tapped out of said suction pipe and extending to the upper surface of said baffle to skim the oil therefrom.

12. In a refrigerating unit, an evaporator comprising a closed tank, an inlet port disposed in one end thereof, a lever pivoted to that end of the tank, a lever valve connected to said lever and operated in and out of said port thereby, a float connected to the free end of said lever, a baffle plate connected to said float above said lever, and a suction pipe terminating above said baffle in juxtaposition thereto.

13. In a refrigerating unit, an evaporator comprising a closed tank, an inlet port disposed in one end thereof, a lever pivoted to that end of the tank, a needle valve connected to said lever and operated in and out of said port thereby, a float connected to the free end of said lever, a flanged baffle plate connected to said float above said lever, and a suction pipe terminating above said baffle in juxtaposition thereto.

14. In a refrigerating unit, an evaporator comprising a closed tank, an inlet port disposed in one end thereof, a lever pivoted to that end of the tank, a needle valve connected to said lever and operated in and out of said port thereby, a float connected to the free end of said lever, a Z-shaped baffle plate disposed with its downward depending flange attached to the float above said lever and its free flange extending upward substantially parallel to the end of the float, and a suction pipe terminating above said baffle in juxtaposition thereto.

15. In a refrigerating unit, an evaporator comprising a closed tank, an inlet port dis-

posed in one end thereof, a lever pivoted to that end of the tank, a needle valve connected to said lever and operated in and out of said port thereby, a float connected to the free end of said lever, a Z-shaped baffle plate disposed with its downward depending flange attached to the float above said lever and its free flange extending upward substantially parallel to the end of the float, a suction pipe projecting through said end above said inlet port and opening upward above said float, and a pipe leading from said suction pipe to a point between the free end flange of said baffle and the end of said float and above said baffle.

In witness whereof, we hereunto subscribe our names this 17 day of Jan., 1930.
